Primary Examiner — Selina Sikder(74) *Attorney, Agent, or Firm* — Nixon & Vanderhye, P.C.(57) **CLAIM**

The ornamental design for "controller for power conditioner for solar energy generation system," as shown and described.

DESCRIPTION

FIG. 1 is front perspective view of the controller in accordance with our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side view thereof; and,

FIG. 7 is a left side view thereof.

Subject matter shown in dotted lines forms no part of the claimed invention.
